UNITED STATES PATENT OFFICE.

BIRGER LJUNGSTRÖM, OF STOCKHOLM, SWEDEN, ASSIGNOR TO AKTIEBOLAGET LJUNG-
STRÖMS ANGTURBIN, OF STOCKHOLM, SWEDEN, A COMPANY OF SWEDEN.

ELASTIC-FLUID TURBINE.

No. 926,814.

Specification of Letters Patent.

Patented July 6, 1909.

Application filed March 15, 1909. Serial No. 483,507.

To all whom it may concern:

Be it known that I, BIRGER LJUNGSTRÖM, a subject of the King of Sweden, and residing at Grefmagnigatan 18, Stockholm, Sweden, 5 have invented certain new and useful Improvements in Elastic-Fluid Turbines; and I do hereby declare the following to be a full, clear, and exact description of the invention, such as will enable others skilled in the art to 10 which it appertains to make and use the same, reference being had to the accompanying drawings, and to figures of reference marked thereon, which form a part of this specification.

15 The present invention relates to an arrangement in radial turbines, having gradual expansion of the driving medium in concentrically placed vane rings, meshing with each other and has more especially reference to 20 the vane disks in such turbines.

The driving medium, which is introduced centrally, will heat the central part of the vane disk or disks to a high temperature and when the driving medium flows outwardly 25 and expands, its temperature falls, and of course the vane disks, which are in contact with the driving medium, will get a high temperature at the center and a low one at the periphery. This difference in temperature will be rather great especially when the vane disks on both sides are passed by the driving medium. The strains in the disks 30 arising from this difference of temperature therein, can easily change the shape of the 35 vane disks, so that these when plane in cold state will buckle or when buckled in cold state will buckle still more. In order that such a change in the shape of the vane disks may not cause that the parts rotating relatively to each other come into contact with each other the play between those parts 40 must be made relatively great, which will cause that the losses on account of the leakage will be unnecessarily great, especially 45 when superheated steam is used, as then the difference in temperature will be considerable, on account whereof the dilatation will be great and the plays must then be made relatively great.

50 According to the present invention the above-named inconvenience will be avoided, since the vane disk is constructed in such a way that it cannot change its shape in axial direction under the influence of the heat.

This is performed by making the disk from a 55 series of rings, arranged in each other and leaving between them in cold state small interspaces. When the rings are heated to different temperatures, they can dilate independent of each other and on account thereof the strains in the disk cannot arise.

60 On the drawing several forms of the invention are shown.

On the Figures 1 and 2 —1—, —2—, —3— and —4— designate four concentric 65 rings, of gradually increasing diameter, which are inserted in each other and partly overlap each other, leaving small interspaces —5— between them. The overlapping parts of said rings are screw-tapped to permit 70 them to be connected with each other by means of screws —6—. The vane rings are marked 7.

In the Figs. 3 and 4, —8—, —9— and 75 —10— are the rings arranged as in Figs. 1 and 2 but connected by means of radially arranged screws —11.

In Fig. 5 the rings are provided with annular grooves or the like —12—, in order that they may be of relatively small weight. 80

In Fig. 6 the rings are provided with flanges —13—, which abut against each other. The rings are connected with each other by means of the screws —14—, passing through the said flanges. The radial 85 strains arising in the rings, cannot by this arrangement be transmitted from the one ring to the other.

In the form shown in Figs. 7 and 8 the rings —15— and —16— are united by means 90 of the flanges —17— abutting against each other and by the ring —18—, abutting against the ring —16— and inserted in a groove in the ring —15—. Between the rings —16— and the rings —19— keys are 95 arranged.

The radial interspaces between the rings can be used as passages for the driving medium, in order to avoid overloading of the turbine and equalize the axial pressure. 100

Claims.

1. In radial elastic fluid turbines, a disk, composed of concentric rings successively increasing in diameter, inserted in each other and having when in cold state interspaces between them. 105

2. In radial elastic fluid turbines, a vane disk, composed of concentric rings, inserted

in each other and partly overlapping each other but successively increasing in diameter and having when in cold state inter-spaces between them, said rings being connected to each other at a few points at the periphery.

3. In radial elastic fluid turbines, a vane disk, composed of rings, inserted in each other and having when in cold state inter-spaces between them, said rings being connected to each other by means of screws.

4. In radial elastic fluid turbines, a vane disk, composed of rings, inserted in each other and having when in cold state inter-spaces between them, said rings being connected to each other by means of screws.

nected to each other by means of screws, extending axially between the rings.

5. In radial elastic fluid turbines, a vane disk, composed of rings, inserted in each other and having when in cold state inter-spaces between them, said rings being provided with annular grooves.

In testimony, that I claim the foregoing as my invention, I have signed my name in presence of two subscribing witnesses.

BIRGER LJUNGSTRÖM.
